United States Patent Office

Des. 210,838

Patented Apr. 23, 1968

210,838

GOLF GAME PUTTING COURSE UNIT

Walter L. Cox, Baltimore County, Md. (8000 Ridgely Oak Road, Baltimore, Md. 21234), and Walter S. Cox, Baltimore County, Md. (3207 Sperl Court, Baltimore, Md. 21234)

Filed June 6, 1967, Ser. No. 7,376

Term of patent 14 years

(Cl. D34—5)

The figure is a perspective view of a golf game putting course unit showing our new design. The sides not shown are plain and unornamented.

We claim:

The ornamental design for a golf game putting course unit, as shown and described.
